VARI-POSITION GOLF CLUB

John W. Hill, Cromwell, Minn.

Application September 16, 1943, Serial No. 502,673

5 Claims. (Cl. 273—79)

This invention relates to a golf club.

It is particularly aimed to provide a construction wherein a surface or angle of a loft may be varied as desired to the end that the club will be adjustable to form a substitute for and perform the function of a plurality of different clubs.

It is also aimed to provide a set of golf clubs wherein two of them will function for all the clubs now used for clubs numbers 1 to 10, and one of which may also be used as a putter.

The more specific objects and advantages will become apparent from a consideration of the description following taken in connection with the accompanying drawing illustrating an operative embodiment.

In said drawing:

Figure 1 is a view of the wooden golf club looking toward the loft surface thereof, the same having the staff broken away;

Figure 2 is a plan view of the parts of Figure 1;

Figure 3 is a longitudinal sectional view taken on the line 3—3 of Figure 2;

Figure 4 is a transverse sectional view taken on the line 4—4 of Figure 2;

Figure 5 is a transverse sectional view taken on the line 5—5 of Figure 2;

Figure 6 is a side elevation of the second, or metallic golf club, the staff being fragmentarily shown and partly in detail to disclose the specific construction; and

Figure 7 is a fragmentary elevation of the staff used in the form of Figure 6.

Referring specifically to the drawing wherein like reference characters designate like or similar parts, and first to the form of Figures 1 to 5, a golf club 10 is shown, having a suitable staff 11 equipped with a head 12 preferably of wood. This club has a loft or face 13 of suitable angle and extending inwardly laterally therefrom is a recess 14 which is occupied by a plurality of relatively movable, removable wooden layers or laminations 15, whose exposed edges are preferably rounded as at 16.

Plates 17 and 18, preferably of brass, and of proper curvature, are countersunk into the lower and upper surfaces of the head 12 as at 19 and 20. Integral with the plate 17 is a bolt 21 which rises through openings 22 and 23 in the head 12 and an opening 24 in the plate 18. The bolt 22 also passes through openings 25 in the laminations 15, the latter affording clearance around the bolt and increasing its diameter in an upward direction as best shown in Figure 4. The laminations 15 are clamped in place with their faces 16

at the desired angle or position by means of a wing nut 26 screw-threaded at 27 on the bolt 21.

A pair of levers formed of rods 28 are pivoted at 29 to the plate 17 and extend upwardly through openings 30 in the laminations 15 and then through transversely elongated slots 31 and 32 provided in the head 12 and plate 18, and with the nut 26 loose, the levers 28 which extend slightly above the plate 18, may be manipulated by the

10 fingers to swing them laterally in order to dispose the edges 16 at any desired angle according to the angle of loft desired, the different angles or positions being suggested in Figure 5 by way of example. Such adjustment is permitted by clearance afforded by the slots 25. After the adjustment is effected, the nut 26 is tightened to clamp the laminations tightly to the edge. The adjustability enables change of the club for a One, Two or Three club.

20 As a companion with the wooden club described, I use a metallic club or iron having a metallic head 33 in connection with which a staff 34 is provided having an opening at 35, pivoted on a pin 36 projecting from one end of the head 33. The staff 34 also has a plate 37 provided with an arcuate slot 38 through which a stud 39 on one end of the head 33 projects and which is engaged by a nut 40 that clamps the staff at various adjustments to the head 33. This club 30 of Figures 6 to 7, can be used for clubs One to Ten and can also be used as a putter.

Various changes may be resorted to provided they fall within the spirit and scope of the invention.

35 I claim as my invention:

1. A club of the class described having a head, laminations in the head providing an angular loft surface, and means operable to move said laminations relatively to each other and to the head to vary the angle of said surface.

2. A club of the class described having a head, laminations in the head providing an angular loft surface, and means operable to move said laminations relatively to each other and to the head 45 to vary the angle of said surface comprising a lever, openings in the laminations through which the lever passes, and clamping means on the head engageable with the laminations.

3. A club of the class described having a head, laminations in the head providing an angular loft surface, and means operable to move said laminations relatively to each other and to the head to vary the angle of said surface comprising a lever, openings in the laminations through which the lever passes, and clamping means on

the head engageable with the laminations, said laminations having clearance openings through which the clamping means passes, and a plate on the head mounting the lever and clamping means.

4. A club of the class described having a head, laminations in the head providing an angular loft surface, means operable to move said laminations relatively to each other and to the head to vary the angle of said surface comprising a lever, openings in the laminations through which the lever passes, a bolt, said laminations having clearance openings through which the bolt passes, a plate on the head mounting the lever and bolt, said plate being on the bottom of the head, a plate

at the top of the head, the latter plate and the head adjacent the same having elongated slots to facilitate movement of the lever and having an opening, and a nut in said opening threaded on said bolt.

5. A club of the class described having a head, laminations in the head providing an angular loft surface, and means operable to move said laminations relatively to each other and to the head to vary the angle of said surface, said laminations at the exposed edges thereof being curved.

JOHN W. HILL.
